UNITED STATES PATENT OFFICE.

EARL W. CLARK, OF SHARON, PENNSYLVANIA.

VEHICLE.

1,303,854.

Specification of Letters Patent. Patented May 20, 1919.

Application filed March 21, 1913. Serial No. 755,907.

To all whom it may concern:

Be it known that I, EARL W. CLARK, a citizen of the United States, residing at Sharon, in the county of Mercer and State 5 of Pennsylvania, have invented a certain new and useful Improvement in Vehicles, of which the following is a full, clear, and exact description.

This invention relates to vehicles, and 10 particularly to motor driven trucks utilized in transporting freight or merchandise.

In a prior application for certain improvements in vehicles invented by E. L. Clark and myself, the said application bearing Serial No. 734,079, filed November 29th, 1912, there are described certain features of vehicle construction, including a separable chassis and body, and means by which the body can be elevated from the chassis and 15 supported independently of the chassis at any point or locality where loading or unloading might be desired. In consequence while the body is being loaded or unloaded, the chassis can be used for other purposes 20 or in connection with other bodies in such a manner that the cost of transporting merchandise is greatly decreased, and the efficiency of the truck service is rendered 25 much higher than is the case if the chassis 30 is idle, while the body is being loaded or unloaded. In the preferred embodiment of the invention described in said application there are utilized a body elevating and supporting means comprising a plurality of 35 legs which are adapted to be connected to the body so as to elevate and support the same independently of the chassis, and when not in use are detached from the body.

The present invention in one of its aspects relates to a somewhat similar body supporting and elevating means, and in this respect, the invention has for its object to provide means by which the supporting and elevating legs are attached to the body in 45 a manner such that when not in use, they can be folded up alongside the base of the body in a compact manner, and when it is desirable to use the same, they can be swung downwardly and moved outwardly to 50 operative position, and firmly positioned with respect to the body, so that the latter can be

elevated and supported very firmly and securely, independently of the chassis.

In another respect, the present invention relates to certain improvements in means for 55 detachably connecting the body and chassis, the object being to provide means by which the body can be locked to or released from the chassis quickly, easily and effectively.

My invention may be here briefly summarized as consisting in certain novel details of construction and combinations and arrangements of parts which will be described in the specification and set forth in 60 the appended claims.

In the drawings, Figure 1 is a side elevation of a truck embodying my improvements, the body being here shown as slightly elevated above the chassis, and being supported by the elevating and supporting legs; 70 Fig. 2 is a transverse sectional view of the same; Fig. 3 is a partial horizontal sectional view substantially along the line 3-3 of Fig. 2, looking downward; Fig. 4 is a side elevation of a portion of the body and chassis, showing the manner of retaining the supporting and elevating legs in inoperative position, or when folded into the body sill; Fig. 5 is a horizontal sectional view substantially along the line 5-5 of Fig. 4, looking 80 downwardly; Fig. 6 is a detail transverse sectional view substantially along the line 6-6 of Fig. 2; Fig. 7 is a detail horizontal view substantially along the line 7-7 of Fig. 2, looking downwardly; Fig. 8 is a 85 transverse sectional view through the chassis and lower part of the body, showing a modification of the locking and unlocking means by which the body can be readily attached to or detached from the chassis; and 90 Fig. 9 is a similar view showing a further modification of the same feature.

Referring now to the drawings, 10 represents the body, and 11 the chassis, both of which may have any suitable construction. 95 The principal requisite, however, of the body and chassis is that the body should be detachably connected to the chassis in such a manner that it can be detached and elevated, or lowered onto the chassis and secured thereto for the purpose of transportation. It may be here stated, however, that 100

my invention has particular utility in connection with folding bodies, for with bodies of that type, I am enabled with a single chassis to distribute a group of empty bodies 5 to various points where loading is desired, as will be hereinafter described. The manner of detachably connecting and disconnecting the body and chassis will be described later.

10 To elevate and support the body independently of the chassis and in a manner such that the chassis can be run from beneath the body when thus supported, or backed underneath the body, so that the 15 body can be again lowered onto the chassis, I utilize a plurality of elevating and supporting legs or jacks 12, two of which are preferably employed at each side of the body. In accordance with the present invention, these legs are attached to the body both when in use, and when not in use, and are in the nature of swinging legs which can be swung from operative position and folded out of the way alongside the lower part 20 of the body. Each of these legs includes in this instance a screw threaded standard or shank 12^a, which is provided at its lower end with a suitable base 12^b, and a relatively movable part 12^c, adapted to travel up and 25 down along the threaded shank 12^a. In this instance, the part 12^c carries a nut 12^d which is provided on the exterior with ratchet teeth adapted to be engaged by a double acting ratchet dog 12^e carried by an operating 30 handle 12^f. The part 12^c of each leg 12 is provided with a laterally extending arm 12^g which has a pivotal connection with the body. It will be observed that the body as 35 here shown is provided along the bottom with side sills 10^a, which are in the form of channels arranged with their flanges extending outwardly. Each of the laterally 40 projecting arms 12^g extends through an opening in the web of the channel and is seated in a socket, including an outer part 45 13 secured to the channel between the outwardly extending legs or flanges, and an inner part 13^a which is secured to the frame in any suitable manner, the inner and 50 outer parts having suitably alined openings through which the arm 12^g freely extends, and in which the arm may turn to swing the leg to or from vertical position. When the legs are in use, or in the position for elevating 55 and supporting the body, they are of course vertical, and the standards or vertical portions are located, as shown in Fig. 2, laterally beyond the body. When the legs are not in use, they are swung 90° from vertical 60 position about the axes of the arms 12^g and are thence moved inwardly into the channels and are retained in that position by suitable spring clips 14, see particularly Figs. 4 and 5. When the legs are so folded,

into the channels, they are out of the way, 65 and have no outwardly extending parts which could act as obstructions.

Preferably on the inner end of the laterally projecting arm 12^g of each leg are two oppositely disposed lugs 12^h which normally 70 prevent the arm 12^g being pulled laterally entirely out from the socket. These lugs are adapted to register with short oppositely disposed sockets or notches 13^b, in the inner end of the inner socket member 13^a, 75 when the leg is swung to vertical position, and thence moved outwardly to elevating and supporting position. The lugs enter into these notches 13^b and assist in holding the legs rigidly in upright position and prevent any relative turning action between the arm 12^g and the socket which receives it. To prevent endwise movement, while the legs are in elevating and supporting position, I prefer to use a tapered key 15 which is 80 adapted to be inserted in a suitably provided opening in the arm 12^g, and when so inserted, bears agains the base of a notch or slot in the outer socket member 13. As before stated, the legs are ordinarily not removed from the body, but with the construction which I prefer, they may be removed when desired. To permit the removal or insertion of the leg with respect to the socket members 13 and 13^a, these two members are 85 provided with a pair of slots 13^c, (see particularly Fig. 5), which slots extend throughout the length of the socket and are oppositely disposed in a plane at right angles to the plane of the oppositely disposed 90 notches 13^b. When the legs are swung to a horizontal position, the lugs 12^h come into alinement with the notches, and accordingly the legs can be removed by withdrawing the arms from the sockets. 95

Another feature of my invention resides in the means for attaching and detaching the body and chassis, as before stated. In Fig. 2, the body is adapted to be detachably connected to the chassis by means of pairs 100 or sets of dogs or levers 17 which are pivotally connected to the chassis, and have at their upper ends hook-shaped portions adapted to be swung outwardly over projecting portions 18, of angle members 18^a, 115 secured to the frame of the body. In the construction shown in Fig. 2, each pair of dogs or legs 17 is adapted to be shifted simultaneously by a screw rod 19 having right and left hand threaded portions which engage in trunnion nuts 20 carried by the lower ends of the dogs or levers. By turning the threaded rod 19, by a hand wheel 19^a, or equivalent means, the two dogs are simultaneously moved toward or away from the 120 coöoperating projections 18 on the body. Between the dogs and below the pivotal connections of the latter with the chassis is a 125

stop member 21 against which one or the other of the dogs may abut to stop the swinging movement thereof by the screw rod in case the chassis is not centrally located beneath the body. If the chassis is not centrally located beneath the body, when the one dog engages the stop, further movement of the screw rod will cause the other dog to shift the chassis laterally in one direction, or to shift the body in the other direction until they are brought into alignment.

In the modification shown in Fig. 8, the body and chassis are adapted to be locked together by pairs of locking members 22 in the form of nuts, two of which are adapted to travel along a screw rod 23, having right and left hand threaded portions engaged by the nuts. This rod is carried by the body and when turned by a crank or other suitable means causes the nuts to move toward or from the side channels or sills of the chassis. The lower portions of the nuts are provided with projecting parts 22^a, which are adapted to be moved under and hence into locking engagement with the upper flanges of channels, the said flanges extending inwardly. Usually two pairs of the traveling nuts will suffice to hold the body and chassis together. With this construction, if the chassis is not centrally beneath the body, the engagement of one nut with the channel will move either the body or the chassis to a position such that the chassis is centrally beneath the same.

In Fig. 9 there is shown a construction in some respects similar to that shown in Fig. 2. In this case, the side sills of the chassis are provided with separate and independent locking dogs or levers 24, which are pivotally connected to the outer sides of the channels, and are adapted to be moved inwardly, so that the hook portions at the outer ends of the dogs will engage over locking pins 25 on the frame of the body. Each of these dogs 24 is adapted to be actuated separately from the other by means of a short screw rod 26, which may be turned by a crank or equivalent means, each of these rods engaging a suitable nut 27 carried by the dog and a nut 28, secured to the chassis.

As was before stated, when the legs or jacks are in position to elevate and support the body, the upright or vertical portions of the legs are located laterally beyond the sides of the body. This arrangement has numerous advantages over an arrangement wherein the legs are beneath or in line with the sides of the body. Among these advantages may be mentioned increased stability, while the body is supported by the said legs; increased clearance between the legs and the wheels of the chassis, this being of particular utility when the chassis is being

backed beneath the body; and permits a number of folding bodies to be placed on the chassis and distributed at the different points at which loading is desired.

To explain the third mentioned advantage, it might be said that a number of folded bodies can be placed one upon the other on the chassis, and can be distributed one at a time by supporting the uppermost body on its elevating and supporting legs, and removing the chassis, and the bodies beneath from the uppermost body, this being rendered permissible only by reason of the fact that the standards or legs, when in operating position, are located laterally beyond the sides of the body.

By employing the adjustable elevating and supporting legs for supporting the body independently of the chassis, the body can be placed at any desired point, practically regardless of any inequalities of the ground beneath the body. A still further advantage in having the elevating means in the legs themselves, lies in the fact that after the chassis runs from beneath the body, said body can be lowered close to the ground. Thus the loading or unloading operation can be accomplished much more easily than would be the case if the body were supported at or above its normal height above the ground, *i. e.*, when supported by the chassis.

Having thus described my invention, what I claim is:

1. In combination, a vehicle comprising a chassis, a body adapted to be supported by the chassis, and detachable therefrom, means for supporting the body independently of the chassis comprising a plurality of adjustable supporting legs, said body having sockets and the said legs having laterally projecting arms extending into the sockets, said sockets permitting an endwise movement of said arms, and a turning movement by which the legs may be swung from a lower vertical position to a position alongside of the body.

2. In combination, a vehicle comprising a chassis, a body adapted to be supported by the chassis, and detachable therefrom, means for supporting the body independently of the chassis, comprising a plurality of supporting legs having pivotal connections with the body, said body having sockets and the said legs having arms which are received in the sockets and are adapted to move endwise in the sockets and to be turned therein, the said sockets and arms having portions which interlock when the said legs are in position for supporting the body.

3. In combination, a vehicle comprising a chassis, a body adapted to be supported by the chassis and detachable therefrom, means for supporting the body independently of the chassis, comprising a plurality of sup-

porting legs having pivotal connections with the body, said body having sockets, and the said legs having arms which are received in the sockets and are adapted to move endwise in the sockets and to be turned therein, each of the said arms having at its inner end a pair of lugs, and the sockets having slots extending lengthwise thereof, with which said lugs register when said legs are turned to one po-

sition, and the said sockets having at their inner ends notches with which said lugs register when the legs are in another position.

In testimony whereof I hereunto affix my signature in the presence of two witnesses.

EARL W. CLARK.
